UNITED STATES PATENT OFFICE.

JULIUS H. SCHLAFLY, OF CANTON, OHIO, ASSIGNOR TO THE CANTON CULVERT COMPANY, OF CANTON, OHIO, A CORPORATION OF OHIO.

CULVERT.

No. 900,039.

Specification of Letters Patent.

Patented Sept. 29, 1908.

Application filed July 22, 1908. Serial No. 444,724.

To all whom it may concern:

Be it known that I, JULIUS H. SCHLAFLY, a citizen of the United States, residing at Canton, in the county of Stark and State of Ohio, have invented a new and useful Culvert, of which the following is a specification.

My invention has for its object to provide a corrugated sheet metal pipe especially designed for drainage purposes, which pipes and sections of pipes are more specifically used in the constructions of culverts, but it will be understood that the purpose of the present invention can be carried out without any specific use, except where drainage is required.

Another object of the invention is to provide sufficient strength without employing heavy and expensive pipe and at the same time provide for perfect drainage.

These objects are accomplished together with a further purpose of providing means whereby the sheets or sections or parts can be nested for shipping and storage.

In the drawing, Figure 1 is a perspective view showing a number of members or sections connected together illustrating one member detached. Fig. 2 is a view showing a number of culvert sections nested. Fig. 3 is a side elevation showing a portion of the culvert proper in section. Fig. 4 is an end view showing a pipe section formed without flanges but embodying the invention.

Similar numerals of reference indicate corresponding parts in all the figures of the drawing.

In the accompanying drawing, 1 represents the culvert members or sections when formed semi-circular or practically so which members or sections are formed of any desired size and when formed to produce substantially one-half of the pipe proper some means should be provided whereby the top and bottom members may be connected together; but the method of connecting the top and bottom sections forms no specific part of the present invention, as it will be understood that the objects and purposes can be carried out by forming the pipe proper in sections without flanges of any description. 50 This construction being clearly shown in Fig. 4. It is well understood that a certain amount of rigidity is required so that when the various sections going to make up a pipe are properly arranged with reference to each other and placed in position there will be no

crushing or collapsing of the pipe. It is also well understood that provision must be made for proper drainage so that there can be no accumulation of sediment by reason of the corrugations 3 formed in the sections. This object is brought about by forming a smooth or non-corrugated part 4, which smooth or non-corrugated part is to be located intermediate the side corrugations 3, said non-corrugated or smooth portion to be located so that it will be at the extreme bottom of the pipe, over which and upon which smooth or non-corrugated part or surface water and sediment are free to pass between the lower or adjacent ends of the corrugations.

By forming corrugations as shown and spacing their inner ends a short distance from each other sufficient rigidity will be maintained in the sections so that when they are placed in position to form a culvert or pipe, they will have sufficient strength to resist crushing force. By corrugating the pipe sections and at the same time forming a portion of the inner surface of said corrugations smooth, the same advantage is accomplished by the use of comparative thin sheet metal, thereby reducing the expense and at the same time maintaining the same advantages that are brought about by the use of heavy and expensive pipe section. In Fig. 4 a cylindrical section is shown, which section constitutes the entire pipe without flanges and the sections connected together at their ends to produce a culvert or system of pipe of the desired length.

It will be understood that the various sections regardless of their specific construction may be connected together by suitable rivets 5 or their equivalents.

Having fully described my invention what I claim as new and desire to secure by Letters Patent, is—

1. A pipe section provided with a plain bottom and corrugated integral portions, substantially as and for the purpose specified.

2. As an improved article of manufacture, a pipe section having a plain portion intermediate its edges and provided with corrugations, said corrugations terminating at their inner ends adjacent the plain portion, substantially as and for the purpose specified.

3. In a pipe of the class described, the combination of pipe sections having smooth

bottoms and integral corrugated portions, substantially as and for the purpose specified.

4. A series of pipe sections or parts, said sections or parts provided with corrugated and non-corrugated surfaces, said non-corrugated surfaces located at the bottoms of the corrugations, substantially as and for the purpose specified.

5. As an improved article of manufacture, a culvert or pipe section or member constructed of metal and provided with flanges and corrugations, the inner ends of said corrugations spaced from each other, substantially as and for the purpose specified.

6. A culvert or pipe consisting of a series of sections or members, said sections or members provided with lateral flanges and the flanges adapted to be connected together and the sections provided with circumferential corrugations formed of a length less than the extreme width of the sections or

members, substantially as and for the purpose specified.

7. A culvert or pipe consisting of sections, each section provided with attaching flanges, said sections provided with corrugations and non-corrugated portions, substantially as and for the purpose specified.

8. A culvert consisting of sections, each section provided with lateral flanges and the flanges adapted to be connected together, said sections provided with corrugations and non-corrugated bottoms located between the lower inner ends of the corrugations, substantially as and for the purpose specified.

In testimony that I claim the above, I have hereunto subscribed my name in the presence of two witnesses.

JULIUS H. SCHLAFLY.
